(57) **CLAIM**

I claim the ornamental design for the duck diver fishing float, as shown and described.

DESCRIPTION

FIG. 1 is a rear view of a duck diver fishing float according to the present design;

FIG. 2 is a left side view of the duck diver fishing float of FIG. 1;

FIG. 3 is a bottom plan view of the duck diver fishing float of FIG. 1;

FIG. 4 is a top plan view of the duck diver fishing float of FIG. 1; and,

FIG. 5 is a perspective view of the duck diver fishing float of FIG. 1 in water with an attached fishing line.

The duck diver fishing float of the present design is shown in FIG. 5 with environmental features that are not aspects of the design. In particular, the water surface at the float level and a fishing line attached to the duck diver fishing float are shown, but are not aspects of the design. The duck diver fishing float includes an elongated neck with a head on one end, a main body with first and second wings on the left and right hand sides, respectively, and a pair of feet and legs pointing in the direction opposite to the head and neck.
